GANG CUTTERS FOR PARING LOG PROTUBERANCES

Thomas W. Nicholson, Auburn, Wash.

Application September 13, 1955, Serial No. 533,996

11 Claims. (Cl. 144—134)

This invention relates to a gang cutter for paring log protuberances and is particularly useful in association with a log barking machine in which a plurality of barker tools are spaced circumferentially about a log, and the log and mounting for such tools are rotated relatively and moved axially simultaneously so that the barker tools follow a spiral path around the log.

It is a principal object of the present invention to provide such a gang cutter which conveniently can be constructed as an attachment for a log barker, such for example as a rotary ring barker which may be of the type disclosed in my copending patent application Serial No. 407,361, filed February 1, 1954. To enable a gang cutter to be attached to such a barker it is an object to make it of compact construction.

A further object is to provide such a gang cutter which will remove from a log protuberances ahead of the barker tools to a diameter which will enable the barker to handle logs of maximum size and so that its capacity will not be curtailed by projecting limb stubs, knots, bumps, other irregularities and excessively flared butts.

It is an object to provide such a gang cutter which will be automatic in operation and will remove protuberances from a log quickly and efficiently.

While the gang cutter is designed ruggedly to withstand severe shock loads, it has a nibbling action so as to avoid imposing large surges in power demand on the barker drive mechanism, and by removing such protuberances in the form of small chips and shavings the material thus removed can be disposed of readily.

In general, the gang cutter includes a cutter bit carrying ring encircling a log and operated in synchronism with barker tools for relative movement circumferentially of the log. Such ring carries a multiplicity of cutter bits projecting a short distance inward therefrom and such ring is ahead of the barking tools so that the cutters will engage protuberances on the log before they reach the barking tools. The cutting bits are preferably of chisel-tooth shape having substantial side rake and end rake, and presenting an acute cutting angle to the log protuberances. Conveniently, the cutter bit carrying ring can take the form of an annular mounting plate disposed in a plane perpendicular to a log moved through it, and the bits can be formed integrally with the leading face of such annular plate as ribs inclined relative to radii of the plate passing through such ribs, respectively, to dispose their inner cutting ends foremost, and such ribs may be of substantially triangular cross section, arranged to present a leading side and having a trailing angle. The preferred types of cutter bit carrying ring and cutter bits are shown in the accompanying drawings.

Figure 1 is an elevation view of a rotary ring log barker equipped with a gang cutter of the present invention, parts of the barker being broken away.

Figure 2 is a detail sectional view through a portion of the barker and gang cutter, taken on line 2—2 of Figure 1.

2

Figure 3 is a perspective view of a fragmentary portion of the cutter bit carrying ring separate from the barker.

A detailed description of a rotary ring barker to which the present gang cutter may be attached may be found in my copending patent application Serial No. 407,361, and feed mechanism for moving a log through such a barker is described in my copending application Serial No. 407,362. A brief description of such mechanism here will therefore suffice to illustrate a typical application of the present gang cutter invention.

To enable my gang cutter to operate on a log it is necessary that a log and the cutter bit carrying ring be moved simultaneously relatively rotatively and axially, so that the log will pass through the ring. While it makes no difference whether the log be moved through the ring, or the ring moved over the log in an axial direction, the barker illustrated in Figure 1 shows a log carried through the ring by rotative ribbed rolls 1 driven by chain 1', against which the log L is held by hold-down wheels 10. The log is moved lengthwise through the barker and gang cutter by rotation of such rolls.

Moreover, while it is immaterial how relative rotation of the cutter bit carrying ring and log is accomplished, the log may be held against rotation by the pressure of wheels 10 pressing the log against the ribbed roll 1, and the barking tools and gang cutter can be rotated. Such a barker may incorporate the ring 2 mounted for rotation in a stationary ring 20, which is supported by slides 21 carried by opposite ends of an upper cross beam 22 and a lower cross beam 23. These slides engage upright guides 24 along which the slides may be moved by frame supporting rods 25, so as to adjust the rings 2 and 20 in a position concentric with a log L supported on roll 1 depending upon the size of the log. The ring 2 carries sprocket teeth 26 which are engaged by a drive chain 27 to rotate such ring relative to stationary ring 20.

As shown in Figure 2, the ring 2 includes two flanges 3 and 30 which are spaced apart axially of the ring a substantial distance to accommodate between them a plurality of swingable arms, preferably four in number, the inner ends of which carry barker tools 4 which preferably are scraper plates. Swinging of the barker tool carrying arms is controlled by air cylinders 34 pivotally supported on the ring flanges 3 and 30 by pivots 35.

As shown in Figure 2, the stationary ring 20 is engaged by wear plates 77 secured on opposite sides of a channel portion of rotary ring 2. These wear plates, which may be of brass, are engageable with opposite sides of an inwardly projecting portion of the stationary ring to resist thrust forces directed axially of the ring. Such plates are in communication with the annular space 73 to which lubricant may be supplied for lubricating the sliding fit between the stationary ring and the plates. Between the stationary ring 20 and the flanges of the U-shaped recess in ring 2 are mounted annular lubricant seal rings 78 sealing the lubricant in the annular space 73. It will be evident that this construction provides a very stable support and accurate guide for rotary ring 2, and such ring itself is of sturdy construction and is therefore well adapted to carry the gang cutter of the present invention.

The gang cutter incorporates the cutter bit carrying ring 100 which, as shown, is preferably formed as an annular plate of considerable radial width. In this plate are provided attaching apertures 101 arranged to register with co-operating apertures in the rotary ring 2 of the barker. Securing bolts 102 extend through the apertures 101 in the gang cutter ring 100 and the apertures in the barker ring 2 for rigidly attaching the gang cutter to the rotary barker ring.

The gang cutter incorporates a multiplicity of cutter bits 103 carried by and projecting inwardly from the bit carrying ring 100 substantially chordwise of the ring and

spaced circumferentially around such ring, preferably equidistantly. A multiplicity of such cutter bits is provided so that the cutter bits will engage any given protuberance on a log in rapid succession to nibble it away, similar to the action of a broach, so as to minimize shock loads on the bits and to avoid large surges in power demand of the barker caused by addition of the protuberance cutter to it.

As shown in the several figures of the drawings the bits 103 project a very short distance inward from the ring 100 and therefore are very strong. These bits are of chisel-tooth shape having an acute, rather small cutting angle, and a substantial amount of bottom rake and side rake to afford ample clearance for the cutting edge despite the rather rapid axial movement of the log as compared to the relative rotative movement between the log and cutter carrying ring. In fact, the trailing face of the bit, as shown best in Figure 3, preferably is of substantially triangular shape.

It is important that the cutting bits be mounted on the ring 100 extremely securely and rigidly, and such construction may be accomplished conveniently by forming the cutting bits as projecting ends of ribs 104 formed integral with and projecting from the leading face of the annular plate 100. These ribs are inclined relative to radii passing through them respectively to dispose their inner bit ends foremost. The inclination of such ribs affords a large top rake and reduces the cutting angle and forms a tool angle of approximately forty-five degrees.

In order that the trailing face of the bit may be of triangular shape as preferred, the ribs 104 are preferably also of triangular cross section and are arranged to present a leading side 105 and a trailing angle 106. The stubby, inwardly projecting ends of such ribs therefore present a rugged chisel bit arranged so that successive bits will pare away small particles or shavings of any log protuberance, whether a branch stub S, as shown in Figure 1, or a bump B, or even a flared butt, so that the log will pass through the rotary barker ring unquestionably and cannot become jammed in it or against it to disrupt operation of the barker.

I claim as my invention:

1. A gang cutter for paring log protuberances comprising a cutter bit carrying ring of a size to receive a log therethrough, and a plurality of bits fixedly secured to said ring in circumferentially spaced relationship and projecting inward therefrom substantially chordwise of said ring.

2. The gang cutter defined in claim 1, in which the bits are chisel-tooth bits.

3. The gang cutter defined in claim 1, in which the bits are chisel-tooth bits having a tool angle of approximately forty-five degrees.

4. The gang cutter defined in claim 1, in which the bits have substantial side rake and bottom rake.

5. The gang cutter defined in claim 4, in which the bottom of the bit is of substantially triangular shape.

6. A gang cutter for paring log protuberances comprising a cutter bit carrying ring of a size to receive a

60

log therethrough, and a multiplicity of bits carried by said ring, spaced circumferentially about said ring at substantially equal intervals and projecting inward therefrom substantially chordwise of said ring.

7. Gang cutting mechanism for paring log protuberances comprising log supporting means, an annular cutter mounting plate disposed in a plane perpendicular to the length of a log carried by said log supporting means and of a size to receive therethrough a log carried by said log supporting means, means operable to effect relative rotative and axial movement simultaneously of said plate and a log on said log supporting means, and a plurality of ribs on the leading face of said plate having ends projecting inwardly beyond the inner periphery of said plate, inclined relative to radii of said plate passing through the respective ribs to dispose their inner ends foremost in the direction of relative rotation of said ring and a log carried by said log supporting means, and the ends of said ribs projecting inward beyond the inner periphery of said plate being formed as cutting bits.

8. The gang cutter mechanism defined in claim 7, in which the ribs are integral with the plate.

9. The gang cutter mechanism defined in claim 7, in which each rib has a leading side of an axial width substantially greater than the axial width of the portion of the bit behind such leading side.

10. The gang cutter mechanism defined in claim 7, in which the ribs are of substantially triangular cross section having a leading side and a trailing angle.

11. Gang cutting mechanism for paring log protuberances comprising log supporting means, an annular cutter mounting plate disposed in a plane perpendicular to the length of a log carried by said log supporting means and of a size to receive therethrough a log carried by said log supporting means, means operable to effect relative rotative and axial movement simultaneously of said plate and a log on said log supporting means, and a plurality of ribs on the leading face of said plate each of substantially triangular cross section with a leading side, having ends projecting inwardly beyond the inner periphery of said plate, inclined relative to radii of said plate passing through the respective ribs to dispose their inner ends foremost in the direction of relative rotation of said ring and a log carried by said log supporting means, and the substantially triangular ends of said ribs projecting inward beyond the inner periphery of said plate being formed as chisel-tooth bits having a tool angle of approximately forty-five degrees.
